ADJUSTABLE BENCH GRINDER

Edward F. Chandler, Brooklyn, N. Y.

Application September 4, 1953, Serial No. 378,539

4 Claims. (Cl. 51—225)

This invention relates to improvements in bench grinders and the like.

An object of the invention is to provide a novel and improved grinding device in which there is a spindle adapted to carry a grinding wheel, and rotated at any desired speed by means of a motor either carried on the grinding device frame, or mounted nearby, and including novel means for holding tools or objects which are to be ground, so that they may be efficiently and quickly ground as needed.

Another object of the invention is to provide a novel and improved grinding device in which the entire device, including motor, spindle, grinding wheel, and adjustable mounting and carrier for the tools to be ground, is made quite compact, and with a low center of gravity, with improved high degree of stability, thus enabling the machine to be placed or mounted on a bench or support in the shop, right at hand convenient for the use of the machinist, in carrying out grinding jobs, so as to avoid waste of time, and permitting several such machines to be used even in a small shop.

A further object of the invention is to provide a novel and improved compact bench grinder of the character described, in which there is a unitary tool support base carried by the frame of the machine, which is adjustable radially from the frame, so as to move the tool which is being ground inwardly or outwardly from the grinding wheel surface, with fine adjustability thereof, the unitary tool support base being also turnable about the vertical axis of the machine frame, to permit grinding either on the outer peripheral edge of the grinding wheel, or on either of its flat faces, or at intermediate angular presentation of the grinding wheel to the tool being ground.

Still another object of the invention is to provide a novel and improved unitary tool support base including a plurality of traverse rods along which the tool post or posts are slidable, thus permitting traverse relative to the grinding wheel of the tool being ground, in any desired or necessary manner.

A further object of the invention is to provide a novel and improved tool chuck arrangement and construction for the tool post or posts, so that a tool to be ground, may be inserted in the tool chuck quickly and easily, and secured therein without need for special tools, but merely by turning one or the other of the hand wheels of the tool chuck, to firmly grip the tool, the tool post which carries the tool chuck being mounted for turning about several axes, substantially universal mounting in effect, so that variously oriented cutting surfaces on machine tools or bits may be ground with a high degree of fineness and precision.

Still a further object of the invention is to provide a novel and improved bench grinder of the character described, which is simple in design, inexpensive to manufacture, highly efficient in use, and which can be made and installed in small and large shops at low cost.

This application is a continuation-in-part of my copend-

2

ing patent application, Serial Number 328,620, filed December 30, 1952, for Universal Grinder, now Patent No. 2,783,592, issued March 5, 1957.

These and other objects and advantages of the invention will become apparent from the following description of a preferred embodiment thereof, as illustrated in the accompanying drawings, forming a part of this application, and in which,

Figure 1 is a front elevational view of my improved bench grinder.

Figure 2 is a top plan view of the bench grinder shown in Figure 1.

Figure 3 is a right side elevational view of the bench grinder, as seen looking from the right of Figure 1.

Figure 4 is a top plan view of the bench grinder, similar to that of Figure 2, except that the tool support frame has been swung or traversed through an angle of ninety degrees about its position of Figure 2, on the vertical main support post, relative to the spindle and motor, this view being in fragment partly.

Figure 5 is a right end elevational view of the tool mounting chuck as might be seen on plane 5—5 of Figure 1, the view showing only the chuck, in engagement with a tool shank.

Figure 6 is a right side elevational view of the chuck shown in Figure 5, the view being partly sectioned substantially on plane 6—6 of Figure 5, and illustrating the mode of engagement at either end of the chuck, with tool shanks of differing diameters, the shanks of the tools being shown in fragment.

Figure 7 is a fragmentary front elevational view of the grinding machine as shown on the same plane as Figure 1, with a toothed cutter mounted in the chuck, with automatic traversing means also shown.

Figure 8 is a right side elevational view of the construction shown in Figure 7, this view including the grinding wheel, in fragment, other parts being omitted for clarity.

Figure 9 is a fragmentary front elevational view taken on the same viewing plane as Figure 7, but showing another type of cutter mounted in the chuck, and including the automatic means for traversing the cutter to maintain contact with the grinding wheel, the parts being shown in fragment.

Figure 10 is a right side elevational view in fragment of the parts shown in Figure 9, as might be seen on plane 10—10 of Figure 9, omitting other parts for clarity.

Figure 11 is a fragmentary top plan view showing a long type of cutter mounted in the chuck for grinding.

Figure 12 is a top plan view showing another type of tapered cutter mounted in the chuck for grinding on the taper.

Figure 13 is a top plan view showing a stepped long shank mounting device for mounting bored cutters prior to being inserted in the chuck, this being used with cutters which have no extensible shanks for this purpose.

Figure 14 is a top plan view showing how an arrangement of the type shown in Figure 13, is inserted in the chuck for grinding of the tool.

Figure 15 is a top plan view showing a cutter mounted in the chuck which has been turned about its vertical axis for being ground by the grinding wheel, another type of shape of grinding wheel being shown in this view for example only.

Figure 16 is a top plan view showing another type of cutter carried in the chuck on a shaft, the chuck having been turned through ninety degrees to present the cutter to the grinding wheel, and indicating in broken lines another position of the grinding wheel relative thereto by further orientation of the parts.

Figure 17 is a top plan view showing another type of bevel cutter mounted in the chuck for grinding, and show-

ing the chuck turned to present the cutter teeth surfaces to the grinding wheel.

Figure 18 is a fragmentary sectional elevational view taken substantially on plane 18—18 of Figure 1.

In the use of bench grinders and the like for various grinding operations in a machine shop, it is necessary that the tool or other part to be ground be easily set up in the grinder without the necessity of improvisation, and yet with the assurance that the tool will be adequately ground and with the desired degree of precision. The grinder should also be small and compact, so that it may be located anywhere in the shop, right at hand for use by the machinist, or even located right on his workbench. Further it should permit of ready insertion and mounting of any of the various types of cutters and the like, with both angular and lateral traverse, so that there will be no surfaces of the cutter which cannot be ground adequately and without delay. The present device is of this character, being an improvement of my copending patent application, Serial Number 328,620, filed December 30, 1952, for Universal Grinder, now Patent No. 2,783,592, issued March 5, 1957.

In order to understand clearly the nature of the invention, and the best means for carrying it out, reference may now be had to the drawings, in which like numerals denote similar parts throughout the several views.

As shown in Figures 1 to 4, there is a stable base generally indicated at 20, and including a floor plate 22 integral with and extending outwardly from the base hub 24, which is somewhat circular when viewed in plan as in Figure 2, the floor plate 22 being intended for support of the electric drive motor 26, the base 23 of which is disposed thereon and secured thereto by any suitable means such as screws 30. The stable base 20 has a base projection 32 integral therewith, and this in turn has an upwardly open socket 34 formed therein to receive the lower end portion 36 of the main upright support post 38. The post 38 may be either seated in the post socket 34 and secured therein by means of a set screw 35 or the like, or may be pressed into the socket 34 and permanently seated therein, as desired.

The upper end portion 40 of the main upright support post 38 extends into the downwardly open bore or socket 42 in the main journal support hub 44, and from Figure 18, it shows that in one form of the invention, the socket 42 may be closed at the top by wall 46, so that hub 44 rests upon the upper end of the main support post 38.

In any event it is preferable that there be no relative turning motion between the base 20, the post 38, and the hub 44 during normal operation of the machine. A main journal or spindle housing 50 may be mounted securely upon the hub 44, or formed integral therewith so as to be firmly supported thereby, and, as seen in Figure 1, in view of the fact that the housing 50 extends for the most part toward the left of the hub 44, a strengthening rib or wall 52 may be formed integral with both the hub 44 and the journal housing 50, to give good support and rigidity. The main journal or spindle housing 50 is provided with a longitudinal bearing bore 54 to receive the rotatable main shaft or spindle 56, which is longer than the housing 50, so that its opposite ends extend substantially outwardly beyond the ends of the journal housing 50. As seen best in Figure 1, a grinding wheel 58 is mounted on the right hand end of the main shaft 56, for rotation therewith, being secured between washers 60 and 62 by means of nut 64 threaded onto the end of shaft 56.

A projection 66 carried by or integral with the journal or spindle housing 50, as seen best in Figure 1, extends upwardly therefrom, and has a lateral bore 68 formed therein to receive the stub shaft 70 which has its outer end secured to or integral with the boss 72 of the shield member 76, so as to support the left wall 74 thereof. As seen, the shield 76 has a curved shield wall 78 which extends partially around the grinding wheel, so as to

catch any abrasive particles or cast off metallic particles of parts being ground, and guide them away from the machinist. A set screw 80 is threaded into an opening in the top of the projection 66, as seen in Figures 1 and 2, so as to permit adjustment of the position of the shield 76 as needed, by loosening the set screw 80 as shown.

At the left end portion of the journal or spindle housing 50, as seen in Figures 1 and 2, there is an upwardly extending mounting lug 82, which is provided with a bore 84 in alignment with the corresponding bore formed in the lug 84 on the angle bracket 86, by means of which a screw 88 is threadedly engaged with members 86 and 82, to secure the parts together as shown. A belt shield housing 90, having an end wall 92 and a skirt wall flange 94 extending therearound and secured to wall 94 or integral therewith, is welded or otherwise secured to the angle bracket 86, being supported thereby. The belt shield housing 90 may also be further secured in position by means of a flange extension 96, secured in any suitable manner to the base 22 to minimize vibration.

The belt shield housing 90 thus defines an enclosure within which the coupling belt 98 moves, so as to transmit power from the motor pulley 100 mounted on drive shaft 102 for movement therewith, to the driven pulley 104, which is mounted on the driven main spindle shaft 56 for rotation therewith. It is thus seen that the driving motor 26 is mounted right down on the lower main base 20, so that its center of gravity is well below the axis of the journal housing 50 and of the grinding wheel 58, thus providing a high degree of stability, and freedom from any tendency to tip over under high grinding stresses. Figure 13 illustrates this stability arrangement wherein the motor is not only placed below the grinding wheel, but also well rearwardly thereof, so that the resultant of any pressure on the grinding wheel while a part is being ground, is directed substantially through the base and hence there is substantially no tendency to tip over at all.

From Figure 2 it is seen that the pulley 100 is of a larger diameter than the driven pulley 104, and it is understood that the ratio of pulley diameters may be varied as needed, to impart any desired speed to the grinding wheel 58.

A main tool support housing hub 110 has a vertical bore 112 formed therethrough as seen best in Figure 18, to receive slidably and turnably the upright cylindrical support post 38, and has a socket bore or recess 114 formed therein at right angles to and intersecting with the axis of the vertical bore 112, to provide a seat for the horizontal bed shaft 116 which is securely seated and secured therein in any suitable manner, as by being pressed therein, welded or brazed therein, or otherwise. As shown, the bed shaft 116 may be substantially rectangular in cross section, but I do not wish to be limited to this shape, such as shown, since it will be understood that other cross sections, including but not limited to cylindrical may be employed, according to other forms of the invention. The bed shaft 116 is of substantial length, and is provided with a cross sectional shape which will block turning motion of any members supported thereby as hereinafter described. The bed shaft 116 thus forms a stable base for carrying slidably the traversing housing 122 which is movable longitudinally along the bed shaft 116 as indicated by the arrow 124 in Figure 2. It is seen that the traversing housing 122 has a bore 126 formed therethrough to receive the shaft 116, and the whole is secured against turning about the axis of the shaft 116 by means of the geometric configuration shown.

The carriage housing or tool support frame housing 122 is thus movable along the bed shaft 116, and a motion limiting or stop member 128 is carried on the bed shaft 116, having an opening 130 formed therethrough to receive the shaft 116. A set screw 132 is threaded through an opening in the member 128, so as to be turnable against shaft 116 to affix the member 128

thereto at any desired location. As seen best in Figure 3, a position adjusting screw 134 is threaded through an opening 136 in member 128, and has its right hand end reduced and extending through an opening 140 in lug 142 of housing 122, with a pin 144 retaining the same in said opening. Hence by turning knurled knob 146, it is possible to finely adjust the traverse of housing 122 axially along the length of shaft 116 in either direction as indicated by arrow 124 in Figure 3. In other words, it is seen that for positioning the housing 122, it is merely necessary to roughly position the housing 122 along shaft 116, and then tighten screw 132. After this is done, it is simple to make a fine adjustment of its position, by merely turning knob 146 to the right or left, advancing or retracting the housing 122 in fine control as needed, relative to the grinding wheel 58. Set screw 141, as seen in Figures 3 and 18, is provided for locking member 122 to shaft 116 at any position as desired.

To adjust the vertical level or elevation of the hub 110 relative to the base 20, and hence of the parts carried by the hub, I provide an integral extension lug 162 extending outwardly from hub 110, and provided with a vertical threaded bore 164 to receive a threaded vertical adjusting and traverse screw 166. A knurled knob or wheel 168 is mounted on or integral with the screw 166 for turning therewith, and the lower portion of the screw, as at 170 may be left unthreaded, and bears downwardly on the upper surface 172 of the rounded bearing plateau portion 174 of the main base 24. To maintain the angular position of the hub 110 and the parts carried thereby, relative to the vertical post 38, a set screw 176 may be employed, being threaded through hub 110 so as to bear against the surface of post 38, or other means may be employed.

As seen best in Figures 1, 2, 3 and 4, the traversing support housing 122 has integral left and right cradle extensions 180 and 182, and the members 122, 180 and 182 have a common upwardly open groove 184 formed therein to form a bed for the rectangular cross section longitudinal traversing bed plate 186, which has an upper plane surface 188, and is of considerable length as seen in Figure 4. Screws 190 are threaded through vertical holes in extensions 180 and 182 and the overlying portions of bed plate 186, so as to secure the plate 186 firmly to the cradle extensions 180 and 182, care being taken to see that the screws 190 do not protrude above the upper surface 188 of the plate.

At the outer ends of the bed plate 186, the end portions 192 of brackets 194 are secured by means of screws 196 extending upwardly through openings in bracket ends 192 and threaded through openings 198 in the plate 186. Here it is seen that the ends 192 of the brackets 194 are formed with upwardly open grooves to receive and fit snugly with the square or rectangular cross section of the plate 186, making for a good solid fit. The end brackets 194 extend outwardly from the plate 186, and have enlarged hubs or bosses 200 formed with openings 202 to receive the ends of the longitudinal traverse slide shaft or support shaft 204, which is either pressed therein or held securely therein by means of a pin or set screw 206. The axis of the shaft 204 is parallel to the axis of plate 186.

A traversing carriage 210 has an integral lower body or bushing 212 with a bore 214 formed therethrough to receive slidably the shaft 204, so that the carriage 210 is slideable either way in the directions of the arrow 216 along the shaft 204. The carriage also has an hub 218 integral with lower body 212, and this has a vertical bore 220 to receive the stub shaft 222 which is vertical as shown best in Figure 3, a pin or set screw 224 serving to maintain the lower hub 226 of the bracket 228 in engagement with the pin 222, which penetrates a vertical bore formed through its hub 226 as shown in Figure 3. Since the example of construction shown has the pin 222 and

hub 226 relatively stationary as to each other, turning of the bracket 228 about the vertical axis of the pin 222 is accomplished in any known manner, one example being by forming a split at one side of the wall of the hub 218, and using the screw 230 to extend across the split wall sections, to draw them together to firmly embrace the pin 222 therein, the grip being loosened by loosening screw 230 when it is desired to turn the bracket 228 to another angular position.

At its upper end, the bracket 228 has a boss or hub 232 with a bore 234 formed through to receive the stub shaft 236 which is integral with and extends out of the tool holder chuck body 238. The bracket hub 232 is split at 240, and has an adjustment screw 242 threadedly engaging one of the lips of the split portions of the hub, which are enlarged somewhat to form lodgment for the screw, so that turning the screw in one direction draws the lips of the split together, clamping it on the shaft 236, and turning the screw the other way, loosens the clamping action. This permits angular traverse of the chuck 238 about the axis of the shaft 236, as indicated by the curved arrow 244 in Figure 1. Graduations may be placed on the surfaces of shaft 236 and boss 232 if desired, to facilitate angular adjustment as needed, as seen in Figure 1.

The chuck body 238 has an axial opening or bore 246 formed therethrough, and has its upper wall split as at 248 through its entire length, with upstanding integral lugs 250 and 252 on each lip of the split, with a tightening screw 254 extended therethrough and threaded into the bore of lug 252, so that the clamping effect of the chuck body 238 around the chuck ring or sleeve 256 may be effected or released as needed. The chuck sleeve 256 may have an annular groove 258 formed in a central portion thereof, as seen best in Figure 6, to receive a corresponding inwardly extending annular rib 260 on the chuck body 238, for maintaining them in mutual engagement against axial movement relative to each other, while permitting turning when desired, upon loosening screw 254 slightly.

Referring now therefore to the detail sectional views of Figures 5 and 6, the chuck 238 is seen to have an axial bore 262 formed through its sleeve 256, with an annular ring member 264 positioned inside the bore 262 and maintained in position by a pin 266 or the like. A set screw 268 may be threaded through the wall of member 238, with its inner reduced end bearing into the annular groove 258 of sleeve 256, as seen in Figure 6, to hold sleeve 256 against turning as desired, or to permit turning the same by loosening the set screw. The ring member 264 has several openings formed therethrough parallel to its axis, these openings or passages being shown as at 270 and extending wholly through the length of ring 264, to allow the six chuck jaw members 272 such as 272a and 272b to extend therethrough at their proximal ends 274, each opening 270 containing the proximal ends of one jaw member 272a and one of 272b, in the manner shown in Figure 6, with pivot pins 276 extending through bores in the jaw members and anchored at their ends in openings formed in the walls of the ring 264, as at 278.

The ring member 264 has an axial bore 280, to allow shanks of cutters 282 and 284, for example to extend therethrough as needed, and it is seen that the working ends of the chuck jaws such as 272a may be made rounded off as shown, or serrated, as desired, and as needed, where they bear against the shanks of the tools. Tightening nuts 285 and 286 are threaded at 288 into the partly threaded outer end portions of the sleeve 256, and have beveled cam surfaces 290 to bear against the taper or beveled surfaces of the jaw members 272a and b, as at 292 and 294, so that as the nuts 285 and 286 are turned inwardly, the jaws 272a and b are moved radially inwardly to securely clamp the shank 282 or 284 of the tools being sharpened. As seen in Figure 6, large or small

tool shanks are easily accommodated, two sizes being shown in the chuck.

As seen best in Figures 2, 3 and 4, the tool support carriage 218 also has an extension foot 300 integral therewith and extending rearwardly over bed plate member 186, so as to lie thereon and be supported thereon. As a result, the carriage 210 is carried not only on the shaft 204 by its sleeve 212, but also rests by its foot 300 on the flat upper surface 188 of bed plate 186. Hence, it is possible to tilt the carriage upwardly about the axis of shaft 204 as seen in Figure 3 when desired, to move the chuck away from the grinding wheel whenever needed.

Referring now to Figures 7 and 8, it is seen that a milling cutter 310 has its shank 312 extending into and engaged in the chuck 238, for being ground or sharpened on the grinding wheel 58, or to bring all its teeth into peripheral alignment by such grinding. In order to maintain the cutter at successive positions whereby each tooth is presented to the grinding wheel surface properly, I provide an indexing holder arm 314 carrying a finger 316 to bear against one of the surfaces of the teeth of the cutter, in the manner shown, the arm 314 extending into an opening 318, and adjustable in position by loosening or tightening the screw 320, which is a set screw threaded through the holder base 322. The base 322 is carried on a shaft 324 extending through an opening in lug 326 mounted on sleeve 328, which is slidably mounted on shaft 204 as shown.

In use, the resilient spring finger 316 will hold the cutter 310 in position against clockwise motion, while a tooth is being ground, but when it is finished, then the operator may turn the cutter in a counterclockwise direction as seen in Figure 8, the spring finger 316 springing past the edge of the tooth, and thus bringing another tooth into grinding position, and serving to hold that tooth in position during the grinding operation. A set screw 330 may be employed to block turning motion of sleeve 328 when needed or desired.

Figures 9 and 10 show how another type of spiral milling cutter 332 may be mounted in the machine for grinding of its cutting teeth by wheel 58. Since the type of cutter 332 may not have a shank, it may be mounted on the arbor device 334 shown in detail in Figure 13, and in applied assembled form in Figure 14 also. The arbor device has a series of stepped shoulders at 336 carried by the shank 338, or even integral therewith, and another series of graduated stepped shoulders at 340 slidably carried on the right end of the shank. The cutter to be carried thereon, such as cutter 332 for example, has the right end of shank 338 inserted through its axial bore, and the left and right assemblies of stepped shoulders are then engaged in the opening in the cutter which fits them, as in Figure 13, the nut 344 being then tightened to secure the whole assembly firmly together to rotate as a unit. When the grinding is finished, the right shoulder unit 340 is removed, and the cutter 332 dismounted. As shown in Figure 9, the shank 338 of the arbor device is engaged in the chuck 238, as also seen in Figure 14, from which view the nuts 284 and 286 are omitted for clarity only, as also in Figures 11 to 17, and is thus ready for being ground by the grinding wheel. In Figures 9 and 14 it is seen that the cutter is mounted on the right side of the chuck 238, while in other views, as in Figures 11, 12 and 15 it is mounted on the left side of the chuck, that is to say, a cutter may be mounted on either side of the chuck for convenience as needed.

Referring also to Figures 9 and 10, it is seen that the indexing arm such as 350, with its resilient finger 352, may be inserted through an opening in base 354, and adjustably positioned therein by set screw 356. The base 354 may have an opening or downwardly open groove or recess 358 formed therein to receive the rectangular bed plate 186, shown in Figures 1 to 4, and a set screw 360 may be employed to adjustably maintain the position of

base 354 as desired. Alternatively, if further adjustability is desired for the arm 350, it may be mounted as at 350a in Figure 9, inserted through the holder 366 and held therein by set screw 368, the shaft 370 being integral with or fixed to holder 366 and extending through an opening 372 in extension 374 of base 354a, being adjustably held by set screw 376. Base 354a is similarly mounted on plate 186 as described for base 354 and seen in Figure 10, and it is clear that more adjustability is available universally in the form shown at the left of Figure 9, that is 350a et sequi.

Figures 11 to 17 show various types of grinding operations and set-ups for various types and shapes of cutters and the like to be ground. In Figure 11, there is shown a long type of milling cutter 380 having a shank 382, which is inserted from the left into the chuck 238, and secured therein by tightening either or both of the nuts 284 and 286 as mentioned for Figures 1 to 4, and 5 and 6. For simplicity, the details of construction of the chuck 238 have been omitted in these views, it being understood that the form shown in Figures 1 to 6 is being used, and the nuts 284 and 286 are also omitted for clarity only. In Figure 11, since the grinding wheel 58 only covers a small part of the cutter, it is necessary to slide the arbor chuck 238 and the support cradle carriage supporting the same back and forth to the right and left as indicated by the arrow 384, to grind the entire length of the teeth of the cutter 380, but this is easily done because of the slidable mounting as already explained.

In Figure 12, there is shown how a tapered milling cutter 386 has its shank 388 inserted in the chuck 238, and the chuck is turned by turning the support bracket 228 shown in Figure 3, to bring the line of the tooth edge 390 into parallelism with the axis 392 of the grinding wheel 58, after which it again is simple to slide the assembly back and forth on shaft 204 as already explained, while grinding each tooth in turn.

Figures 13 and 14 have been already explained in conjunction with Figures 9 and 10, hereinabove, and show how an arbor device 338 is used to insert through a bore in a cutter 332 having no shank, to mount the cutter for grinding.

Figure 15 shows another set up for grinding with a tapered grinding wheel 58b, mounted on the spindle shaft 56, it being necessary to employ such grinding wheels for grinding some types of cutter surfaces. In this instance, the cutter 394 has been mounted with its shank 396 engaged in the chuck 238, and the chuck has been turned on its bracket 228, as in Figure 3, out of parallelism with the axis of the shaft 56, and it is apparent that by use of various shapes of grinding wheels mounted on the spindle 56, and adjustment of the positioning of the cutter to be ground, practically any desired surface of a cutter or other object may be ground to perfection with ease.

Figure 16 shows still another type of cutter 396 having still another type and shape of cutting teeth, and shows how the cutter is mounted on the arbor 398 which is inserted through an opening in the cutter axis, and the arbor in turn is inserted and engaged in the chuck 238. In this instance, the chuck has been turned through an angle of ninety degrees so that the axis of the arbor 398 is now perpendicular to that of the grinding wheel 58 and its spindle 56, permitting grinding along the margin of the cutter 396 as shown. It is also seen that if the direction of grind is to be changed for some reason or other, it is simple to shift the position of the chuck 238 to the left, in which case the position of the grinding wheel would then be that shown at 58a.

Figure 17 shows how a bevel V-cutter 400 can be mounted in chuck 238 for grinding of its teeth on one side, 402, and then the position of the parts can be changed easily because of the universal slidable mounting, to grind the other side 404.

The various types of grinding operations shown in Figures 7 to 17 are merely examples and illustrative of what

can be done in some cases. However, those skilled in the art will understand clearly from the hereinabove stated description that this machine is quite easily used for substantially all grinding operations, and on substantially all objects which are to be ground or sharpened. For further aid in quick adjustment, various of the knobs shown, such as the knob 146, for traverse of the cradle along shaft 116, may be made in the form of a handwheel with a small knob, for quick and accurate turning thereof, and graduations may be shown on shaft 116 to permit of accurate positioning and adjustment for any desired depth of grind.

Although I have described my invention in specific terms, it will be understood that various changes may be made in size, shape, materials and arrangement without departing from the spirit and scope of the invention as claimed.

As shown best in Figure 6, leaf springs 410 may be disposed in each opening 270 or secured to ring 264 in any suitable manner, so that opposite legs of the springs bear radially outwardly against the undersides of the chuck jaw members 272a and 272b, to bias them radially outwardly, thus allowing free unblocked insertion of shanks 282 or 284 of tools therein when the cam nuts 284 or 286 are in their outwardly retracted positions, as shown for nut 286 in Figure 6. As shown in Figures 1 and 2, the hub 110 may be split as at 409, lugs 412 and 414 forming enlargements of the split edges, and the screw 416 being used to clamp them together, releasably, permitting angular traverse about a vertical axis.

I claim:

1. A chuck comprising a chuck body having an opening formed therethrough and open at both ends, a chuck sleeve secured in said opening and having an axial bore open at both ends, an anchor block carried on the inner side of said axial bore of said chuck sleeve and having an axial bore formed therethrough, first and second pluralities of chuck jaw members pivoted to said anchor block and oriented so as to extend toward opposite end openings in said sleeve, each plurality of jaw members extending toward one of said sleeve openings, cam surfaces on said jaw members, and cam nuts carrying cooperating cam surfaces and threaded to opposite ends of said sleeve and constructed and arranged for extension inside and retraction out of said sleeve, whereby upon extension inside said sleeve said jaw members are cammed inwardly to grip firmly any tool shank inserted therein to hold the same securely to said chuck.

2. The construction according to claim 1, characterized

further in that there is resilient spring means constructed and arranged in said sleeve opening for normally biasing said chuck jaw members apart from each other, to allow free entry therebetween of a tool shank or the like to be secured therebetween.

3. The construction according to claim 1, wherein said chuck comprises an integral trunnion shaft, a bracket for supporting said chuck body and including a bearing to engage said trunnion shaft, whereby said chuck body may be oriented angularly through a complete circle of adjustments, and clamp means carried by said bracket, for holding said chuck body in any selected adjustment position.
4. The construction according to claim 1, wherein said chuck comprises an integral trunnion shaft, a bracket for supporting said chuck body and including a bearing to engage said trunnion shaft, whereby said chuck body may be oriented angularly through a complete circle of adjustments, clamp means carried by said bracket for holding said chuck body in any of said angular positions, a bracket 15 base member, said bracket pivotally engaging said base member for turning adjustment about a vertical axis, means for clamping said bracket base member and said bracket together in any of said angular positions about said vertical axis, whereby said chuck is universally 20 mounted.
5. The construction according to claim 1, wherein said chuck comprises an integral trunnion shaft, a bracket for supporting said chuck body and including a bearing to engage said trunnion shaft, whereby said chuck body may be oriented angularly through a complete circle of adjustments, clamp means carried by said bracket for holding said chuck body in any of said angular positions, a bracket 25 base member, said bracket pivotally engaging said base member for turning adjustment about a vertical axis, means for clamping said bracket base member and said bracket together in any of said angular positions about said vertical axis, whereby said chuck is universally mounted.
